UNITED STATES PATENT OFFICE

WILLIAM I. SMITH, OF BROOKLYN, NEW YORK

TOY

Application filed April 4, 1929. Serial No. 352,432.

This invention relates to improvements in toys, particularly to a novel toy bath tub and it is the principal object of my invention to provide a toy in form of a bath tub in which the water level is indicated or represented by a sheet of transparent material, as for instance celluloid which simultaneously serves as a holding means for two toy figures, preferably the representations of children sitting in the bath tub and facing each other.

Another object of my invention is the provision of a toy for amusing children, of simple and therefore inexpensive construction, yet durable and efficient in its purpose of amusing and occupying the mind of children and at the same time acting as an educational demonstrative directing the children's mind to the value of cleanliness.

A further object of my invention is the provision of a toy in form of a bath tub containing a wash rag and sponge.

These and other objects and advantages of my invention will become more fully known as the description thereof proceeds, and will then be specifically defined in the accompanying claims.

In the accompanying drawing, forming a material part of this disclosure:

Fig. 1 is a longitudinal section through the toy constructed according to my invention, along line 1—1 of Figure 2.

Fig. 2 is a top plan view of the toy.

As illustrated, on the drawing, the representation of a conventional bath tub 10 made of celluloid or any other suitable material has arranged therein the representations of two children 11 and 12 in sitting posture, facing each other, and having their limbs 13 and arms 14 horizontally and parallel to each other extended in front of their bodies to simulate gladness of taking a bath while their facial expressions illustrate convincingly their joy of being in the water.

The water level in the bath tub is represented by a sheet 15 of transparent material, having its edges snugly fitting against the inner walls of the bath tub and resting on a shoulder 16 formed with the bath tub. Suitable openings cut in the material of the sheet 15 allow the placing of the figures into

the tub and their walls serve at the same time as holding means to keep the toy figures in place and in erect posture.

A wash rag 17 and a sponge 18 are conveniently placed in the bath tub within easy reach of the children's representations.

It will be evident from the above description and simultaneous inspection of the drawing that I have produced a simple toy of great merit as a toy as well as an educational demonstrative which will greatly contribute to occupy the child's mind and direct it to cleanliness.

The toy can be floated in a wash basin or tub greatly to the delight of the children and will constitute an everlasting source of delight and joy for children.

It will be understood that I have shown and described the preferred form of my toy only as one example of the many possible ways to practically make the same and that I can make such changes in its shape, material, or construction as come within the scope of my invention without departure from the spirit of my invention and the principles involved.

Having thus described my invention, what I claim as new and desire to secure by Letters Patent is:

1. Toy in form of a bath tub comprising a sheet of transparent material within said tub representing the water level and having openings formed therein, means formed with said tub to support the sheet, two figures representing bathing children in said tub, held therein by the walls of said sheet openings, and washing paraphernalia in said tub.

2. Toy representing a conventional bath tub and comprising an inner shoulder, a sheet of transparent material within said tub, said sheet being perforated, two figures representing bathing children in sitting posture in said tub held therein and washing and cleaning paraphernalia within said tub.

3. Toy representing a conventional bath tub of floating material, an inner shoulder formed therewith, a perforated sheet of transparent celluloid within said tub resting on said inner shoulder and representing the water level in said tub, figures of children

facing each other and in sitting posture on the bottom of said tub, extending through the perforations in said sheet and held in position by the walls of said perforations and a wash rag and sponge within said tub.

4. A toy representing a conventional bath tub comprising an upper scroll for said tub and an inner shoulder formed in the walls of said tub, a perforated sheet of translucent material resting on said shoulder and snugly engaging the inner walls of said tub, a pair of toy figures of floating material in sitting posture in said tub, their upright bodies held in correct position by the walls forming the perforations in said sheet, said figures facing each other and having joyous facial expression, arms and legs on said figures extending from the bodies thereof, and a wash rag and sponge within said tub.
